UNITED STATES PATENT OFFICE.

GUSTAV A. MAYER, OF STAPLETON, NEW YORK.

DESIGN FOR A PASTRY-WAFER.

SPECIFICATION forming part of Design No 17,150, dated March 1, 1887.

Application filed October 4, 1886. Serial No. 215,327. Term of patent 14 years.

To all whom it may concern:

Be it known that I, GUSTAV A. MAYER, of Stapleton, in the county of Richmond and State of New York, have invented a new and original Design for Wafers, of which the following is a specification.

The nature of my design is fully shown in the accompanying drawings, in which—

Figures 1 and 2 are perspective views of my newly-designed pastry.

This invention relates to wafers having the shape of rolls or tubes or flat sheets.

The main feature of my design consists in a wafer having cone-shaped projections on one surface.

A represents a rolled or tubular wafer. B are cone-shaped projections on the surface of the same at regular intervals. A' represents a flat wafer, and B' cone-shaped projections

on the face of the same at regular intervals. The projections B or B' rise conspicuously from the face of the wafer, and those parts of the wafer between the projections are flat.

Having thus described my design, I desire to secure by Letters Patent—

The design, substantially as herein shown and described, for pastry-wafers consisting of a flat or rolled wafer having numerous cone-shaped projections at regular intervals on its surface, that part of the surface of the wafer between the projections being flat.

In testimony that I claim the foregoing as my invention I have signed my name in presence of two subscribing witnesses.

GUSTAV A. MAYER.
